UNITED STATES PATENT OFFICE.

WILLIAM A. HATCH, OF EAST CLEVELAND, OHIO, ASSIGNEE TO THE CHILCOTE COMPANY, OF CLEVELAND, OHIO, A CORPORATION OF OHIO.

DISPLAY DEVICE.

Application filed November 27, 1925. Serial No. 71,624.

This invention, relating as indicated, to display devices, has more particular reference to display devices of ornamental character such as to be suitable for supports or 5 mounts for fine photographs, pictures, etc. Among the objects of the invention are the provision of a display device or mount which can be stood in self-supporting or easel-like position, and which can be locked or 10 positively secured against accidental displacement from such position. A further object is the provision of connecting means allowing the device to be set up in position of use or be collapsed flat without requiring 15 assembling. A still further object is the provision of a construction directed toward the elimination of sagging or distortion in shape on long continued standing. Other objects will appear as the description proceeds.

20 To the accomplishment of the foregoing and related ends, the invention, then, consists of the means hereinafter fully described and particularly pointed out in the claims, the annexed drawing and the following description setting forth in detail certain features embodying the invention, such disclosed means constituting, however, but several of various forms in which the principle 25 of the invention may be used.

30 In said annexed drawing:

Fig. 1 is an isometric view of one form of embodiment of the invention; Fig. 2 is a similar view of a modification; Fig. 3 is a plan view of a blank for assembly; Figs. 4 and 5 are plan views of face panels; and Fig. 6 is a central vertical section through a set-up device.

As shown in the form of the invention illustrated in Fig. 1, etc., the device comprises 40 members 1 and 2 adapted to be set up so as to stand in generally upwardly directed position, these being advantageously integrally joined as at 3; and projecting from one of the members, ordinarily what would be the 45 back or supporting member, is a connecting member 4. Advantageously, this latter is integrally joined with the member 2 and has at its extremity a tongue or projection 6 adapted to engage in a slideway 9 in the 50 other member, it being held in engagement with such slideway by laterally projecting lugs 7. The slideway 9 is cut so as to allow of a sufficient excursion of movement therein for the connecting member 4 to be slid up 55 and allow the entire device to collapse down

flat, the connector 4 being then interlayered between the face 1 and back member 2. Preferably a keeper or locking flap 10 is cut so as to be positionable against the tongue 6 in the slot when the device is in set-up relation and thus prevent further movement of the tongue in the slideway, so as to hold the parts in fixed relation. The shoulders 8 of the connector member are preferably left full width so as to abut snugly against the 60 face member 1 and thus afford support clear across.

Advantageously, the device may be cut from sheet stock, for instance card board of ornamental character suitable for fine mount 70 usage, the particular material of course being a matter of choice and in some instances fiber or sheet metal may be employed. By arranging the cutting dies to suitable design, the blank may be cut and scored at one operation, the tongue 6 with its lugs 7 being cut at one end, a guideway 9 with the displaceable locking member 10 being cut toward the opposite end portion, and the 75 folds 3, 5 and 11 being also scored in.

While a photo or the like can be directly secured by its four corners to the face member 1, I prefer generally an ornamental face panel 12 secured at one or more points by adhesive or other suitable means to the face 80 or front member 1, it being preferably provided with diagonal cuts 13 toward each corner to receive the photo print or other article to be mounted.

In the form shown in Fig. 2, the face panel 90 14 is of a character to provide protecting flaps or shutters 15. Advantageously, a panel of this type is cut from sheet stock and at the same time is scored as indicated at dotted lines 16 (Fig. 5) so that when secured to the 95 face member 1, the shutters 15 can be folded back so as to expose a photo or other picture which may be mounted inside, or where desired such shutters can be laid down in closed or protecting position. In this manner, there 100 is provided a mount which has the additional feature of face protecting means.

The manner of use of my improved mounts will be readily understood. The blank form in which the device is initially manufactured 105 is assembled by folding along the dotted lines 3 and 5 (see Fig. 3) and the tongue 6 is inserted by a slightly diagonal turn through the guideway 9, the flap 10 being turned back out of the way for this purpose. 110

The tongue 6 is then slightly folded up so as to lie substantially parallel with the face member 1, and with the keeper or locking flap 10 slightly turned so as to be in an inactive position the tongue 6 may be slid back and forth in the slideway 9 for either the set-up position as in Fig. 1 or for the collapsed flat position. When set up, the keeper or locking flap 10 is set against the tongue 6 and thus prevents its further sliding movement and the device is then positively secured in its position of use as in Fig. 1. By the employment of various panels such as shown in Figs. 4 and 5, photos or pictures to be mounted may be made up in various desired forms, and as seen, the device affords a display mount which is capable of being collapsed flat for shipping or handling, but which may be quickly set up into position of use, no further manipulation being required therefor than the mere sliding of the tongue 6 into its lower position and the setting of the locking flap 10 thereagainst. In such position the device is well braced at the point of most needed support so that even with long continued standing, it is guarded against sagging. While ordinarily after having once been assembled, the device may be used in set-up or in collapsed positions without being disassembled, should occasion arise it may very readily be disassembled however, by slightly displacing the locking flap 10 so as to allow the tongue 6 to be turned diagonally sufficiently to be withdrawn from the guideway 9.

Other modes of applying the principle of my invention may be employed instead of those explained, change being made as regards the features herein disclosed, provided the means stated by any of the following claims or the equivalents of such stated means be employed.

I therefore particularly point out and distinctly claim as my invention:—

- 45 1. An article of the character described, which comprises two members adapted to stand in generally upwardly directed position and joined at the top, and a connecting member adapted to extend from one of said members to present an engaging end movable within a path in a concealed slideway in the other member, whereby without withdrawal thereof from the slideway the said two members may be also collapsed together.
- 50 2. An article of the character described, which comprises two members adapted to stand in generally upwardly directed position and joined at the top, and a connecting member adapted to extend from one of said members to present an engaging end movable within a path in a concealed slideway in the other member, said connecting member having lugs for normally preventing disengagement

ment from such slideway, whereby without withdrawal thereof from the slideway the 65 said two members may be also collapsed together.

3. An article of the character described, which comprises two members adapted to stand in generally upwardly directed position and joined at the top, a connecting member adapted to extend from one of said members to present an engaging end movable within a path in a concealed slideway in the other member, whereby without withdrawal thereof from the slideway, the said two members may be also collapsed together, and a locking flap engageable against said connecting member.

4. An article of the character described, which comprises front and rear members adapted to stand in generally upwardly directed position and joined at the top, and a member adapted to extend from the base of the rear member to present an engaging end movable within a path in a slideway in the other member, said connecting member having lugs for normally preventing disengagement from such slideway, whereby without withdrawal 90 thereof from the slideway, the said two members may be also collapsed together.

5. An article of the character described, which comprises front and rear members adapted to stand in generally upwardly directed position and joined at the top, a member adapted to extend from the base of the rear member to present an engaging end movable within a path in a slideway in an intermediate and upper zone of the front member, said connecting member having lugs for normally preventing disengagement from such slideway, whereby without withdrawal 95 thereof from the slideway, the said two members may be also collapsed together.

6. An article of the character described, which comprises front and rear members adapted to stand in generally upwardly directed position and joined at the top, a member adapted to extend from the base of the rear member to engage by a tongue in a slideway in the intermediate and upper 115 zone of the front member, said connecting member having lugs for normally preventing disengagement from such slideway, a locking flap extending from the upper end of the slideway to engage against said connecting member, and a face panel over the said front member.

Signed by me this 25th day of November, 1925.

WILLIAM A. HATCH.
